UNITED STATES PATENT OFFICE.

EUGENE V. MYERS, OF EAST ORANGE, NEW JERSEY.

SHOCK-ABSORBER.

1,160,976.

Specification of Letters Patent

Patented Nov. 16, 1915.

Application filed November 17, 1906. Serial No. 343,631.

To all whom it may concern:

Be it known that I, EUGENE V. MYERS, a citizen of the United States, residing at East Orange, in the county of Essex and State of New Jersey, have invented certain new and useful Improvements in Shock-Absorbers, of which the following is a specification.

This invention relates to so-called shock absorbers for automobiles and other vehicles and aims to provide certain improvements therein.

In motor cars or other vehicles having springs the latter are normally at a considerable tension due to the weight of the body of the vehicle and the occupants. When a "bump" or temporary elevation is encountered the first effect is to compress the spring still further, as the car body tends to maintain the position in a horizontal plane in which it is moving, this being particularly true when the car is in rapid motion. The secondary effect which closely follows the compression of the spring is that the car body is thrown violently upward due to the reaction of the spring. When a depression in the road-bed is encountered a reverse movement takes place. The car body tends as before to maintain its horizontal plane, and the running gear tends to drop away from the body, this action taking place because the spring is relieved temporarily from the weight of the body. The latter being temporarily unsupported gravity overcomes its inertia and it moves downward violently compressing the springs beyond its normal condition. It has been the practice heretofore to provide an absorber adapted to check such violent reactions of the spring, but such absorbers have been so constructed that they act at all times during both the action and reaction of the spring. Obviously, any drag which is placed upon the spring during what may be called its "action," that is to say during its yielding movement when the wheels pass over an elevation or depression, partially destroy the action of the spring. Theoretically the spring should be as yielding as possible during such action and should not be stiffened by the interposition of any retarding device during such time.

According to my invention in its preferred form I provide a shock absorber which is adapted to permit the spring to yield freely

without any retarding effect in either direction from its normal condition. When, however, the running gear and body seek to resume their normal relative positions a retarding effect is produced which permits them to resume such positions gradually so that a secondary violent movement of the car body is avoided. By my invention, however, a lesser degree of retardation may be imposed upon the spring during its primary movements and a greater degree during the secondary movements, if desired. So also the absorber may be constructed in such manner that no retarding effect is placed upon the spring during those slight movements which occur from minor variations in the road-bed, the retarding effect being introduced only in the major movements of the spring and body and such retarding effect may be produced as just stated, or may be imposed during both the primary and secondary movements. My invention also renders it possible to graduate the degree of retardation so that it is less during the minor movements of the parts and greater during the major movements thereof. In its preferred form my invention provides an absorber which permits the use of a very flexible spring with the minimum danger of breakage of the latter and at the same time one in which the minimum jarring effect is transmitted to the car body. All danger of crystallization of the axle is avoided and wear upon the tire and shock to the running gear and driving mechanism is reduced.

In the drawings, wherein I have shown several embodiments of my invention, Figure 1 is a diagrammatic view illustrating the movements of the running gear upon encountering an elevation and a depression. Fig. 2 is a central vertical section of my invention as applied to an absorber acting hydraulically. Fig. 3 is a central section of my invention as applied to a frictional retarder. Fig. 4 is a section on the line 4—4 in Fig. 3. Fig. 5 is an elevation of another form of frictional retarder. Fig. 6 is a section on the line 6—6 in Fig. 5. Fig. 7 is an elevation of one of the disks of Fig. 5, and Fig. 8 is an elevation of another of the disks, showing its inner side. Fig. 9 is a section of Fig. 5 taken upon the line 9—9 in Fig. 7. Fig. 10 is a section of a modified form of hydraulic retarder. Fig. 11 is a

rear view of a motor car illustrating a method of applying absorbers in accordance with my invention.

Referring first to Fig. 1 of the drawings, let A indicate a vehicle body, B one of the axles of the running gear, and C one of the wheels. During normal running the spring D is compressed by the weight of the body and the load to a certain extent, the axle being in a position relative to the car body indicated by the line X—X. When an elevation or "bump" is reached the first effect is to throw the wheel and axle upwardly, the car body tending to maintain its normal horizontal plane by inertia. The spring momentarily yields and flattens as shown in dotted lines, until the axle reaches its uppermost position indicated by the line Y—Y. Immediately following the compression of the springs the inertia of the body is overcome and the spring tends to throw the body upwardly. Such upward movement of the body is not illustrated. The parts then assume their normal position with a violent motion which carries the body first beyond the normal position and by a series of vibratory movements the normal position is then reached. During the ascent of the axle to the plane Y—Y preferably no retarding effect is imposed upon it. During the first movement of the body toward the axle however, its movement is retarded, preferably to such extent that it does not tend to move beyond its normal position. Upon a depression being encountered upon the road the normally compressed spring permits the wheel to drop into the depression while the body maintains substantially its normal position, the axle assuming a position indicated by the lines Z—Z. Immediately after this movement the body tends to drop violently toward and past its normal position. This movement of the body is not illustrated. The parts finally assume the relative positions in which they normally rest, after more or less violent movements of the body. During the descent of the axle the spring is permitted to act freely, but during the first movement of the body downwardly it is retarded, preferably to such an extent that it does not move past its normal position. By thus permitting the spring to act freely upon a change in either direction from its normal position a much greater retarding effect can be safely introduced on the return movement. In the present constructions wherein the absorber acts to retard a relative movement of the parts in all directions, the retarding effect must be limited on the return of the parts to that which can be safely imposed during their primary movement. This effect cannot be considerable since it would deaden the spring during the time when the spring action is most needed viz. during its primary movements.

My invention is capable of embodiment either in a hydraulic device or in one which acts frictionally. I will first refer to Fig. 2, wherein I have illustrated the former. In this construction let E indicate a hydraulic cylinder provided with an eye a by means of which it can be pivoted to the axle. In the cylinder E works a piston F the rod b of which passes through a stuffing box to the exterior, its free end being provided with an eye c by means of which it may be pivoted to the car body. The cylinder E is provided with two passages e f leading from its opposite ends and connected at its middle to the cylinder by a passage g. Each of the passages e f is provided with a valve h or i which is normally held closed by a spring j. The piston F is shown in its middle position which corresponds to the normal position of the spring during the running of the car. When the running gear is thrown upwardly by meeting an elevation the piston moves to the left, forcing the oil or other fluid with which the cylinder is filled out through the passage e, lifting the valve h and flowing freely around through the passage g into the cylinder at the rear of the piston. As the car body and axle commence to assume their normal positions the piston starts to move to the right and the valve h seats itself immediately. The piston is thus prevented from returning to its normal position any faster than the oil leaking around it will permit, thus producing a retarding effect upon its movement. An adjustable plug valve k may be provided in the cylinder to regulate the movement of the piston, and in this case the piston may make a tight fit with the cylinder. When a depression is reached in the road bed the piston F moves toward the right as the axle recedes from the car body. As the parts tend to assume their normal positions the piston moves to the left toward its normal position and an action takes place similar to that just described, the piston moving freely to the right and with a retarded movement to the left. The passages d e and valves h i should be of sufficient capacity to permit the free movement of the piston in the appropriate direction. If it is desired, however, to produce a slight retarding effect upon the primary action of the spring this can be done by proportioning the passages so that they are not capable of passing the oil as fast as the latter is normally forced through them. The same effect may also be accomplished in various other ways. An important feature of the present construction is the provision of the passage g by means of which the oil is permitted to reenter the cylinder at the rear of the piston after passing through either of the valves. The length of this passage longitudinally of the cylinder may be approximately the width of the piston. By increas-

ing the length of the passage (as shown in dotted lines) the piston may be permitted to play freely without any retarding action for any desired distance and the car body and 5 axle may thus be retarded only during their more extreme movements. If it is desired for any reason that the movements shall be retarded in both directions the valves *h* *i* may be omitted and the passages *d* *e* re-10 stricted to the desired extent. Under these circumstances a limited amount of free play is permitted, while the major movements of the spring and body are retarded. Means may be provided in this or in any other construction for graduating the retarding effect. 15 As one instance of such means I have illustrated a groove or grooves *l* which are shown as tapered from the ends of the cylinder toward the middle. This has the effect of 20 permitting more or less oil to leak past the piston on the retarding stroke or strokes, thus graduating the retarding movement. In constructions wherein it is desired to retard the piston in both directions the grooves 25 may be similarly arranged, or may be reversely arranged so that an increased retarding effect is obtained as the piston approaches its normal position.

The invention is capable of embodiment 30 in many other constructions of hydraulically acting devices than that illustrated. For instance instead of the cylinder a barrel may be employed, and instead of the reciprocating piston a rotary piston may be used. In 35 this case the piston and barrel may be provided with arms pivoted to the axle and car body. The valves instead of being arranged in the cylinder may be placed in the piston; in this case the piston may be formed with 40 two heads, each carrying a valve and spaced apart sufficiently to permit the oil to flow between them, thus closing one valve and opening the other.

My invention is capable of embodiment in 45 friction devices of various kinds, two of which I have illustrated in Figs. 3-9.

Referring first to Fig. 3 let *G* indicate a cylindrical or other piston having its bore enlarged at *n*. In the cylinder *G* work two 50 expandible pistons or friction devices *H* and *I*. *J* is a rod adapted to be pivoted to the car body and connected to the pistons *H* by toggles *o*, *o* which are pivoted to the semi-cylindrical sections *p*, *q* of the pistons. The 55 two sections of each piston are pivoted to a cross bar *r* through which the rod *J* works. Each section is provided with an arm *s* or *t*, one of which, as *s* is screw threaded to receive a sleeve *u* which engages a head 60 formed on the opposite arm *t*. By screwing the sleeve upwardly or downwardly the limit of motion of the sections *p*, *q* is adjusted. The device illustrated in Fig. 3 works similarly to the device illustrated in 65 Fig. 2. Each piston may move freely to-

ward its end of the cylinder and is expanded on the return stroke toward normal position. When one piston is moved toward the end of the cylinder the opposite piston plays idly in the expanded bore *n*, 70 notwithstanding that its toggle is being moved to press the sections apart. Nuts *v*—*v* are provided for limiting the contractile movement of the sections, although the same effect may be obtained by the edges 75 of the sections coming together.

In Figs. 5-9 I have illustrated a device of similar form to a well-known frictional absorber. In these figures 2 indicates an arm which is adapted to be pivoted to the vehicle body and 3 indicates a similar arm adapted to be pivoted to the axle. The arm 2 has formed at its end a disk 4 and the arm 3 a disk 5. At the left of the disk 4 is a disk of leather 6, and at the left of this disk is a metal disk 7. The parts are held together by a bolt 8 which has a non-rotative connection with the disk 7 and disk 5, and a rotative connection with the disks 4 and 6. Preferably the bolt is squared at its 85 points of connection with the disks 5 and 7. A star spring 9 is pressed against the disk 5 by nuts 10 and 11 and serves to place a variable compression upon the parts.

Referring to Figs. 7-9 the disk 4 is provided with recesses 12 and 13 on its inner face and the disk 5 is provided with a series of spring-pressed friction dogs 14, 15, 16 and 17 which play in recesses 19, 20, 21 and 22. Two of these recesses 19 and 20 are 90 illustrated in Fig. 9. They are tapered in such manner that the dogs 14 and 15 can move in one direction from the position shown in Fig. 8 without exerting any substantial friction upon the parts, while in the opposite direction the dogs are pressed toward the small ends of the recesses and are moved outwardly against the disk 4 moving the disk 5 to the right. This action forces the bolt 8 to the right pressing the disk 7 95 against the leather disk 6, and as the parts move toward their normal position the bolt 8 is rotated carrying with it the disk 7 and producing a retarding movement. The dogs are preferably held in position by pins 25 100 passing through slots formed in the dogs. The working faces of the dogs of the disk 4 or both may be roughened to insure a certain engagement sufficient to actuate the dogs, if desired. When one of the dogs is 105 moving out of the recess 12 the other one is playing idly in the recess. The same action takes place with the dogs 16 and 17. The dogs instead of being the shape shown in Fig. 9 may be circular in form, and pivoted eccentrically, or any other shape of dog may 110 be provided.

In Fig. 10 I have shown a modified form of hydraulic device. In this figure the cylinder 28 is formed with an enlargement 29, 115

and the piston 30 is formed with two perforated heads 31 and 32. The piston is not directly connected with the piston rod 33, but the latter carries two disks 34, 35 which are adapted to contact with the heads 31 and 32 and form in effect valves for the latter. As the piston rod moves to the right the disk 35 is brought into contact with the head 32 and moves the piston to the right. 10 The oil flows around the disk 34, through the head 31 and around the head 32, through the passage 29 to the rear of the head 32. On the return stroke the disk 34 contacts with the head 31 and closes it partially and 15 then moves the piston 30 to the left. During this movement the opening through the piston being restricted the piston is retarded. The disks may wholly close the piston if desired, and the oil may leak around the heads 20 31, 32 or through small openings 37 in the disks.

In the frictional devices illustrated a desired amount of free play of the parts can be obtained by lengthening the recesses *n* in 25 Fig. 3, and 12 and 13 in Figs. 7 and 9. The retarding effect may be graduated in both these constructions by tapering the walls leading to the recesses.

It is obvious that many other forms of device may be constructed to perform the 30 functions necessary to my invention, and I therefore do not wish to be limited in any way to the forms shown.

It is a part of my invention to provide 35 means having different degrees of retarding effect, or combinations of free movement and retarding effect, in a single complete movement of the axle and body from one extreme to the other. The precise movements or parts of movements in which such effects are applied is immaterial, since I believe myself to be the first to adapt a retarding or absorbing device to a normal position of the parts, and to produce different 40 retarding or absorbing effects, or combinations of such effects and free play of the parts, on movements toward or from such positions. I also believe myself to be the first to vary the retarding or absorbing 45 effects during either a complete movement of the parts or during a partial movement thereof.

My invention also provides a construction 50 in which the absorber acts to retard sidewise movements of the body relatively to the running gear. One such construction is shown in Fig. 11, wherein the absorbers 40, 41 are arranged obliquely transversely of the car, instead of longitudinally thereof. Preferably the same absorbers are adapted to retard both the vertical and sidewise movements, one set effecting both results. Other absorbers than that provided by my invention may be arranged as shown, or in any

other way which will effect the desired result.

By my invention I provide a means by which a retarding effect may be obtained during any desired part of the relative movement of the vehicle and axle, and such effect does not drop off so rapidly as to give practically no retarding action beyond that which is theoretically possible for a very slight portion of the movement of the vehicle and axle from their extreme positions. In the claims I have used the term "substantially constant" to indicate the action of my device. This does not mean that the degree of retarding effect may not be varied, as by the supplemental graduating grooves shown in Fig. 2, but such variation should not be carried to the extent of producing no substantial retarding effect upon the vehicle during most of the return movements of the body and axle. My invention also includes means which are capable of retarding such movements whether of maximum or moderate amplitude. For instance in Fig. 2 there is a retarding effect upon the piston from any point it may assume, although such effect may be varied at will by any desired tapering of the groove.

I do not herein claim specifically the construction shown in Figs. 3 to 9 and 11, since such constructions form the subject-matter of a divisional application filed by me October 16th, 1915, Serial No. 56218.

What I claim is:

1. The combination with a vehicle of a retarding device connected with the body and axle thereof, and adapted to permit a relative movement of the body and axle in either direction from a normal intermediate position, said device having means whereby a substantially constant retarding effect may be produced upon the return movements toward such position and a lesser or no retarding effect upon the initial movements away from such normal position.

2. The combination with a vehicle of a retarding device connected with the body and axle thereof, and adapted to permit a relative movement of the body and axle in either direction from a normal intermediate position, said device producing a retarding effect upon the return movements in either direction toward such position and a lesser or no retarding effect upon the initial movements away from such normal position, and means for adjusting the degree of the first named retarding effect.

3. The combination with a vehicle of a retarding device connected with the body and axle thereof, and adapted to permit a relative movement of the body and axle in either direction from a normal intermediate position, said device producing a retarding effect upon the return movements in either

direction toward such position and a lesser or no retarding effect upon the initial movements away from such normal position, and said device having means for adjusting the 5 degree of said first named retarding effect, extending to the exterior of the device.

4. The combination with a vehicle, of a retarding device having means whereby a substantially constant retarding effect may 10 be produced upon relative movements of the vehicle body and axle in both directions toward a normal intermediate position which retarding effect is greater than upon relative movements in opposite directions away from 15 such position.

5. The combination with a vehicle, of a retarding device having means whereby a substantially constant retarding effect may be produced upon relative movements of the 20 vehicle body and axle in both directions toward a normal intermediate position which retarding effect is greater than upon relative movements in opposite directions away from such position, and said device having supplemental means for graduating such retarding 25 effect.

6. The combination with a vehicle of a retarding device arranged between the running gear and body, said retarding device 30 adapted to act freely from a normal intermediate position in one direction and having means whereby a substantially constant retarding effect may be produced in the opposite direction toward such normal position, 35 but not past the latter.

7. The combination with a vehicle of a retarding device arranged between the body and axle thereof, and comprising a member 40 connected to the running gear, a member connected to the vehicle body, means for permitting a substantially free relative movement of said members in both directions away from a normal position, and means for retarding their return movements toward 45 such position, such means being adapted to produce a substantially constant effect.

8. The combination with a vehicle of a retarding device arranged between the body and axle thereof, and comprising a hydraulic 50 chamber, a piston adapted to normally occupy a central position therein, means for permitting the liquid to pass substantially freely from one side of the piston to the other as the piston moves away from such 55 central position in either direction, said means tending to oppose movements of the piston in either direction toward such central position, and leak passages through which the liquid passes on such movements, 60 the effective areas of said passages being unaffected by the movements of the piston.

9. The combination with a vehicle, of a retarding device arranged between the body and axle thereof, and comprising a hy- 125

draulic chamber, a piston adapted to normally occupy a central position therein, means for permitting the liquid to pass substantially freely from one side of the piston to the other as the piston moves away from such central position in either direction, said 65 means tending to oppose movements of the piston in either direction toward such central position, and leak passages through which the liquid passes on such movements, said passages being unaffected by the movements of the piston, and a supplemental passage, the effective area of which is gradually varied by the movements of the piston. 70

10. The combination with a vehicle, of a retarding device arranged between the body and axle thereof, and comprising a hydraulic chamber, a piston adapted to normally occupy a central position therein, valves adapted to open when the piston moves away from such position in either 80 direction, and to close when it moves toward such position in either direction, and passages adapted to permit a substantially uniform flow as the piston moves toward such 85 position.

11. The combination with a vehicle, of a retarding device arranged between the body and axle thereof, and comprising a hydraulic chamber, a piston adapted to normally occupy a central position therein, 95 valves adapted to open when the piston moves away from such position in either direction, and to close when it moves toward such position, passages adapted to permit a substantially uniform flow as the piston 100 moves toward such position, and means for adjusting such passages.

12. The combination with a vehicle, of a retarding device arranged between the body and axle thereof, and comprising for vehicles a hydraulic device adapted to permit the axle and body to move substantially freely away from a normal position to points beyond such position in both directions, and having means adapted to provide a substantially constant retarding effect from such 105 points toward such position.

13. The combination with a vehicle, of a retarding device arranged between the body and axle thereof, and comprising for vehicles, a hydraulic cylinder, and a piston for moving therein, and means for permitting said piston to move in either direction from a central position with a less retarding effect than toward such position, such means being adapted to provide a substantially constant retarding effect on movements toward such central position. 115

14. The combination of a vehicle, the axle and body of which occupy an approximately 120 normal position, and means interposed between said axle and body and acting to retard the movements of the axle and body in

either direction toward such position, said means being adapted to provide a substantially constant retarding effect in such movements, and to provide a lesser or no retarding effect by movements of said axle and body away from such position.

In witness whereof I have hereunto signed

my name in the presence of two subscribing witnesses:
